UNITED STATES PATENT OFFICE.

ELIHU THOMSON, OF LYNN, MASSACHUSETTS, ASSIGNOR TO GENERAL ELECTRIC COMPANY, A CORPORATION OF NEW YORK.

LEAKAGE-PREVENTION ARRANGEMENT FOR FUEL-TANKS.

1,365,567.

Specification of Letters Patent. Patented Jan. 11, 1921.

Application filed September 8, 1919. Serial No. 322,471.

To all whom it may concern:

Be it known that I, ELIHU THOMSON, a citizen of the United States, residing at Lynn, in the county of Essex, State of Massachusetts, have invented certain new and useful Improvements in Leakage-Prevention Arrangements for Fuel-Tanks, of which the following is a specification.

The present invention relates to fuel tanks such as gasoline tanks used to supply fuel to engines, and has for its object to provide an improved structure and arrangement whereby should a hole be made in the fuel tank nevertheless it will not leak.

One particular application of my invention is in connection with fuel tanks for the engines of aeroplanes where a leak in the tank, caused, for example, by a bullet, may be a very serious matter. Another application of my invention is in connection with fuel tanks for the engines of boats or other apparatus where leakage may occur and where it is not always convenient to immediately repair the same. My invention however, is not limited to these applications but may be utilized wherever found applicable.

For a consideration of what I believe to be novel in my invention, attention is directed to the accompanying specification and the claims appended thereto.

In the drawing Figure 1 is a diagrammatic view partly in section of an arrangement embodying my invention; Fig. 2 is an end view on a smaller scale of the fuel tank shown in Fig. 1 and Fig. 3 is a sectional view of a modification.

Referring to the drawing Figure 1 indicates an internal combustion engine provided with a suitable carbureter 6 to which fuel is supplied by a conduit 7. The discharge outlet 8 of the carbureter is connected to the intake manifold 9 of the engine and the air inlet 10 of the carbureter is connected to an air conduit 11 through which air is fed to the carbureter. The engine and carbureter arrangement shown may be taken as typical of any such apparatus. The operation is well understood and needs no description.

Now according to my invention, I provide a fuel tank for the engine and a suitable pumping means for pumping fuel from the lower portion or bottom of said tank and feeding it to the carbureter. I also provide in connection with the fuel tank a second

pumping means, which may be in the form of a suction fan, and which is connected to the top of the fuel tank above the level of the fuel therein, so as to maintain a partial vacuum therein. With this arrangement, in case a hole is made in the tank producing a leak, then instead of fuel leaking out of the tank through the hole, air will be sucked into it through the hole and discharged by the pump means which creates the partial vacuum in the tank. By this means leakage of fuel through the hole will be prevented. To minimize the leakage which may occur due to a hole in the fuel tank, I provide the tank with an inner jacket or lining of a felted mass which is so strongly woven that it will partially close a perforation made through it. Or instead of a felted mass I may use any other material which will accomplish the desired result.

The air pumped from the fuel tank by the vacuum producing pump means will always contain some fuel vapor and in case of a hole in the tank, will be highly carbureted. To avoid inflammable vapors floating around, and also to utilize them, I connect the discharge side of the vacuum producing pump means to the air inlet of the carbureter so such vapors will be fed to the engine. I also provide suitable means for controlling the vacuum producing pump means and for admitting air to dilute the mixture discharged by such pump means when too highly carbureted.

Where the apparatus always remains in vertical position, the two pump means may be connected directly with the bottom and the top of the fuel tank respectively. In cases, however, where the angle may vary, such as, for example, aeroplanes and ships, I preferably arrange the apparatus so that the two pump means always remain connected with the bottom of the tank and with the space above the fuel therein, irrespective of the angle which the fuel tank may be in.

In Figs. 1 and 2, I have illustrated the latter arrangement. 12 indicates a fuel pump which may be of any suitable type and driven and controlled in any suitable manner. In the present instance, a reciprocating pump is illustrated driven by an eccentric 13 on a shaft 14. The suction and discharge valves for pump 12 are indicated

at 12^a and 12^b. The discharge side of pump 12 is connected to supply conduit 7 and the suction side is connected to a suction pipe 15. The fuel tank, indicated at 16, is lined 5 with a felted material 17, as referred to above, and is made in the form of a flat drum with disk like ends. Fuel tank 16 is rigidly supported with respect to the engine and at the center of one end is provided with a 10 tube 18 which projects into the tank about half way and is rigidly fixed to the tank. The free end of pipe 15 extends through the center of the tube 18, being supported therein by a spider 19, and is closed by a plug 20. 15 Pivots on the ends of tube 18 and pipe 15 is an air conduit 21, the outer end of which terminates near the top of the tank and above the level of the fuel therein. The inner end of conduit 21 communicates 20 with tube 18. It is desirable that conduit 21 turn freely on tube 18 and pipe 15. Accordingly, between conduit 21 and tube 18 is a suitable ball bearing 22, over which is placed a flap of soft material 23, such as 25 leather or the like. This covers the joint and prevents fuel from leaking through the joint into the air conduit. The end of pipe 15 is located in a bearing sleeve 24 carried by conduit 21. Depending from conduit 21 30 is a fuel pipe 25, the outer end of which terminates adjacent the bottom of tank 16 and carries a weight 26, the purpose of which is to keep conduit 21 and fuel pipe 25 always in vertical position, as shown in Fig. 35 1. The inner end of pipe 25 projects through conduit 21 and communicates with the interior of a housing 27, which is pivotally mounted on pipe 15 inside air conduit 21. In pipe 15 are one or more holes 28 which connect the interior of pipe 15 with housing 27. 40 It will thus be seen that air conduit 21 and fuel pipe 25 form an integral structure which can turn freely on the ends of tube 18 and pipe 15 and which is always maintained 45 in a vertical position due to weight 26.

Connected to tube 18 outside tank 16 is an air pipe 29, which leads to the suction side of a suction pump 30. Pump 30 is shown as being a centrifugal suction fan 50 and its discharge conduit 31 is connected to air conduit 11. Pump 30 may be driven in any suitable manner. In discharge conduit 31 is a controlling valve 32 adapted to be operated by rod 33. Valve 32 is used to regulate pump 30. By closing it to a greater or lesser extent the pressure on the discharge side of the pump will be increased thereby diminishing the quantity of air pumped. In other words, closing valve 32 more or less 60 increases the resistance to the flow of air through pipe 31, thereby diminishing the amount of air handled by the pump. Connected to conduit 31 is an auxiliary air inlet conduit 34, in which is a valve 35 adapted to 65 be controlled by rod 36.

In operation, fuel pump 12 pumps fuel from tank 16 through pipes 25 and 15 and delivers it through pipe 7 to carbureter 6. At the same time air pump 30 maintains a partial vacuum in tank 16, the air and vapors pumped out being drawn out through conduit 21, tube 18 and conduit 29 and delivered through conduit 31 to air conduit 11, and thence to the engine. Auxiliary air valve 35 will normally be closed and 75 valve 32 will be set to give the desired regulation to pump 30. If, now, fuel tank 16 should have a hole made through it, for example by a bullet passing through it as indicated in Fig. 3 at A, then instead of 80 fuel leaking out, air will be sucked in through the hole or holes and delivered by pump 30 to the air inlet of the carbureter. If this air is too highly carbureted, valve 35 may be opened to dilute the mixture to the 85 desired extent.

The arrangement shown in Fig. 1 is one well adapted for use in connection with an aeroplane and it will be clear that due to air conduit 21 and fuel pipe 25 being pivoted on the ends of tube 18 and pipe 15, even should the aeroplane fly up-side-down, nevertheless, air conduit 21 and fuel pipe 25 will remain vertical. Air conduit 21 will thus remain connected to the space above 95 the fuel in tank 16 and fuel pipe 25 will remain in communication with the bottom thereof.

In Fig. 3 I have shown an arrangement which may be used where the angle of the 100 tank is not subject to change. In this case air conduit 29, corresponding to air conduit 29 of Fig. 1, is connected directly to the top of fuel tank 16^a and fuel pipe 15^a, corresponding to fuel pipe 15 at Fig. 1, is connected directly to the bottom thereof. Otherwise, the arrangement may be the same as that of Fig. 1.

In accordance with the provisions of the 110 patent statutes, I have described the principle of operation of my invention, together with the apparatus which I now consider to represent the best embodiment thereof, but I desire to have it understood that the apparatus shown is only illustrative and that the 115 invention may be carried out by other means.

What I claim as new and desire to secure by Letters Patent of the United States, is:

1. The combination with an engine, a fuel tank, and means for supplying fuel 120 from the tank to the engine, of pump means for sucking air from the top of said tank to continuously maintain a partial vacuum therein, and a valve means on the delivery side of said pump means for regulating 125 said pump means.

2. The combination with an engine, a fuel tank, and means for supplying fuel from the tank to the engine, of pump means for sucking air from the top of said tank to main- 130

- tain a partial vacuum therein, the discharge side of said pump means being connected to said engine, and means for admitting air to the discharge side of said 5 pump to dilute the mixture delivered by it.
3. The combination with an engine, a fuel tank, and means for supplying fuel from the tank to the engine, of pump means for sucking air from the top of said tank to 10 maintain a partial vacuum therein, means for regulating said pump and means for admitting air to the discharge side of said pump means to dilute the mixture delivered by it.
- 15 4. In combination, an engine, a fuel tank, a conduit through which fuel is fed from the tank to the engine, an air conduit connected with the tank, and means connected with the air conduit for maintaining a partial 20 vacuum in the tank, said fuel conduit and air conduit being so arranged that the fuel conduit always communicates with the bottom of the tank and the air conduit with the top thereof.
- 25 5. In combination, an engine, a fuel tank, a conduit through which fuel is fed from the tank to the engine, an air conduit connected with the tank, said two conduits terminating within the tank, and conduit 30 means pivotally mounted on said conduits and connecting them with the top and bottom of the tank.
6. In combination, an engine, a fuel tank, a conduit through which fuel is fed from the 35 tank to the engine, an air conduit connected with the tank, said two conduits terminating within the tank, and conduit means pivotally mounted on said conduits and connect-
- ing them with the top and bottom of the tank, said conduit means being weighted so 40 as to always remain vertical.
7. In combination, a fuel tank, a conduit through which fuel is withdrawn from the tank, a conduit through which air is withdrawn from the tank to maintain a partial 45 vacuum therein, and means whereby said fuel conduit and air conduit are maintained in communication respectively with the bottom and top of said fuel tank irrespective of the angle which said tank may assume. 50
8. In combination, an engine, a fuel tank, a pipe for delivering fuel from the tank to the engine, an air pump, a suction pipe connecting the suction side of the air pump to said tank, and a discharge pipe connecting 55 its delivery side to said engine, the arrangement being such that said fuel pipe and suction pipe are always in communication with the bottom and top of said tank respectively, and means for regulating said air 60 pump.
9. In combination, an engine, a fuel tank, a pipe for delivering fuel from the tank to the engine, an air pump, a suction pipe connecting the suction side of the air pump to 65 said tank, and a discharge pipe connecting its delivery side to said engine, the arrangement being such that said fuel pipe and suction pipe are always in communication with the bottom and top of said tank respectively, 70 and means for admitting air directly to said discharge pipe.

In witness whereof, I have hereunto set my hand this fifth day of September, 1919.

ELIHU THOMSON.
